UNITED STATES PATENT OFFICE.

WILLIAM C. DOWNING, OF CHICAGO, ILLINOIS.

COMBINATION TICKET-PUNCH.

SPECIFICATION forming part of Letters Patent No. 781,594, dated January 31, 1905.

Original application filed April 8, 1903, Serial No. 151,610. Divided and this application filed July 23, 1903. Serial No. 166,703.

To all whom it may concern:

Be it known that I, WILLIAM C. DOWNING, a citizen of the United States, residing at Chicago, in the county of Cook and State of Illinois, have invented new and useful Improvements in Combination Ticket-Punches, of which the following is a specification.

This invention relates to improvements in that class of devices forming the subject-matter of an application filed by me on the 8th day of April, 1903, Serial No. 151,610, and of which this is a division.

The figure in the drawing is a vertical longitudinal section of a device embodying the improved features.

The drawing in this application is a duplicate of Figure 3 in the application referred to; but the description will be limited to the construction, arrangement, and operation of the ticket-punching dies and the mechanism for actuating the same.

The casing or body A supports the different working parts and may be of any desired contour best adapted for the purpose. Access is had to the lower interior part of the casing through an opening closed by a removable cap B. The under side of the casing is provided with a rigid handle C, a manipulating lever-handle D being pivotally mounted in the upper part thereof. The inner end of the manipulating-handle D extends into and is secured in its working position in the casing by a pivot-pin 2, inserted through the hollow head-end extension 3 thereof. The pivot-pin 2 is located about midway between the head end 3 of the casing and the enlarged bearing part 4 of the lever-handle, as shown. The upper end of a coiled spring 5 is recessed in the under side of the lever-handle, the lower end being seated in the casing, as at 6. A ticket-canceling punch 7 is mounted on the inner end of the lever-handle and is adapted to traverse a ticket-slot 8 by an upward movement in practical working, the punched-out portion escaping through a die-aperture 9.

A second punch, 10, is mounted on the enlarged part 4 of the lever-handle and traverses a ticket-slot 11 by a downward movement, the cut-out portion escaping through a die-aperture 12. The first punch may be used for

general canceling purposes when the tickets are of a class not requiring to be numbered. The second punch, 10, is more especially intended for commutation-tickets that are usually canceled by "snipping" out a printed number with the edge portion of the ticket. A third canceling-punch, 13, is located at the rear end of the casing and is carried and supported by the cap B. This punch traverses ticket-slot 14 by a downward movement, the portion canceled from the ticket dropping out through a die-aperture 15. This third punch is actuated by an inclined supplemental lever 16, located underneath the outer part of the lever-handle. The outer end of lever 16 is loosely supported in a lug 17, formed on the corresponding end of the lever-handle and provides for a slight endwise movement thereof in conforming to the change of position when being worked. The inner end of lever 16 is pivotally connected to the casing, as at a, and bears on the upper end of punch 13. This punch is positioned to traverse the ticket-slot through which the numbering or printing mechanism is reached and is intended for the class of tickets that are to be both canceled and numbered, this dual operation being simultaneously effected by one down movement of the lever-handle, which imparts a corresponding movement to the outer end of lever 16, and the inner end having a fulcrum-bearing on the punch 13 forces the same down across ticket-slot 14. A spring 18 returns this punch to its normal position when the compressing pressure on the main lever-handle is relaxed. The punch 13 is prevented from turning around in its working position by a pin 19, fixed in the casing and projecting into a vertical slot 20, formed in the adjacent side of the punch-stem.

By having a punch-die located in position to traverse the ticket-slot opening to the printing-disks 21 saves both time and labor, as the necessity for inserting the same ticket a second time is avoided. The plurality of canceling-punches also provides an individual punch for the different classes of tickets and the cutting-face of each punch may be of a different design or character as a distinguishing feature in keeping a record.

A detail description of the printing mechanism and other parts not indicated by reference characters nor relating directly to the canceling mechanism will be omitted in this case, as these features are fully set forth in the pending application herein referred to and in prior patents granted to me.

Having thus described my invention, what I claim, and desire to secure by Letters Patent, is—

1. In a combination ticket-punch, a casing provided with a rigid handle part, a manipulating lever-handle movably mounted in said casing, a punch-die located within the casing and mounted on the inner end of the lever-handle in advance of its pivotal bearing, a second punch-die inclosed within the casing and mounted on said lever-handle back of its pivotal bearing, a third punch-die mounted on the rear end of the casing, and a supplemental lever interposed between said third punch and the lever-handle, whereby the different punch-dies are simultaneously actuated with each manipulation of the lever-handle, substantially as set forth.

2. In a combination ticket-punch, a casing, a lever-handle pivotally mounted therein, a

punch-die mounted on the back end of the casing and traversing the ticket-slot 14, and a supplemental lever having its outer end supported from the corresponding end of the actuating lever-handle and the inner end pivoted to the casing and bearing on the upper end of said punch-die, substantially as set forth.

3. In a combination ticket-punch, a casing having a ticket-slot in the back end thereof, a manipulating lever-handle pivoted in said casing, a supplemental lever having its inner end pivoted in the casing and its outer end supported from the corresponding end of the lever-handle, a punch-die positioned to be forced downward across the ticket-slot by the contact of said supplemental lever, and a spring mounted on said punch and returning the same to its normal position when the punching pressure on the same is released, substantially as set forth.

In testimony whereof I have signed my name to this specification in the presence of two subscribing witnesses.

WILLIAM C. DOWNING.
